UNITED STATES PATENT OFFICE

2,071,022

TROMBONE

Joseph F. Burke, Somerville, Mass.

Application May 1, 1936, Serial No. 77,292

3 Claims. (Cl. 84—395)

This invention relates to trombones and particularly to means for lubricating the portions of the inner tubes which telescope within the limbs of the shoe or slide.

5 In using a trombone it is desirable to keep these portions of the inner tubes thoroughly lubricated, because if there is insufficient lubrication the proper manipulation of the shoe portion of the trombone is interfered with which makes it difficult for the musician to play the notes accurately.

10 The usual way of lubricating the portions of the inner tubes of the trombone which telescope within the shoe is for the musician to deposit oil on such portions from an oil can, but it is not always easy or convenient to do this during the rendition of an orchestral composition. In the case of a trombone player in a band which is playing outdoors or while marching there is often 15 necessity for frequently lubricating the trombone and this cannot be conveniently attended to while the trombone player is marching with the band.

One of the objects of my present invention is 20 to provide an improvement in trombones by which the desired lubrication of the inner tubes may be accomplished by a movement of the slide.

In order to give an understanding of the invention I have illustrated in the drawing a selected embodiment thereof which will now be described after which the novel features will be pointed out in the appended claims.

In the drawing:

Fig. 1 is a fragmentary view of a trombone showing parts in section and illustrating one construction embodying the invention.

Fig. 2 is a section on line 2—2, Fig. 1.

Inasmuch as the invention relates merely to the lubrication of the portions of the inner tubes which telescope within the shoe or outer slide, I have not thought it necessary to illustrate herein a complete trombone. In the drawing 1 and 2 indicate the two inner tubes of a trombone which communicate with the mouthpiece and the bell respectively, neither of which are herein illustrated. The inner tube 1 may be that which communicates with the mouthpiece and the inner tube 2 that which leads to the usual bell.

The usual shoe portion or outer slide of the 50 trombone is indicated at 3, this having the usual U-shaped construction and having the two tubular legs 4 and 5 which telescope over the portions 6 and 7 of the inner tubes. The legs 4 and 5 of the shoe are connected by the usual brace or handle portion 8 by which the shoe is moved back

and forth on the inner tubes and the two inner tubes 1 and 2 are also connected by a brace or handle member 9 as usual in trombones. In the present invention each inner tube 1 and 2 has an oil reservoir associated therewith, and means are provided by which oil from each reservoir may be deposited automatically on the portion of the corresponding inner tube which needs lubrication by the movement of the shoe or outer slide 3.

The inner tube 1 is formed with a casing or jacket 10 surrounding it which forms between it and said tube an oil reservoir 11. A similar jacket or casing 12 surrounds the inner tube 2 and forms therewith an oil reservoir 13. The handle or brace 9 is shown as tubular in form and it connects the two casings 10 and 12, the interior of the handle 9 communicating with each oil reservoir. The handle is shown as having a filling opening 14 into which oil may be introduced into the reservoirs and a removable closure plug 15 is provided for closing the filling opening 14.

Each oil reservoir is equipped with a valve through which oil is deposited onto the portion of the corresponding inner tube which needs lubrication. As herein shown the end 16 of each reservoir is provided with a port 17 adjacent the inner tube and situated within each reservoir is a spring-pressed valve disk 18 having a tapered projection 19 which extends through the port 17. Each valve disk 18 is acted on by a spring 20 which encircles the inner tube within the oil reservoir and which normally holds the valve seated. When each valve disk 18 is resting against the end 16 of the oil reservoir the tapered projection 19 of the valve disk will fill and entirely close the port 17, thus preventing any leakage of oil. This is the normal condition.

If, however, either valve 18 is raised so as to partially withdraw the projection 19 from the port 17 then oil may seep out of the port 17 onto the adjacent portion of the inner tube, thereby providing the desirable lubrication. The opening of the valves may be accomplished by the movement of the shoe or outer slide, for by moving the shoe toward the reservoirs the ends 21 of the legs 4 and 5 will be brought into engagement with the projections 19, thereby raising the valves so that oil may flow through the valves onto the inner tubes, thereby providing the necessary lubrication.

It will be observed that this operation of opening the valves can be accomplished simply by a movement of the shoe and such movement can be quickly given even when the trombone is being played. Hence, if a trombone player finds that

his trombone needs lubrication while he is using it in either a band or an orchestra he can quickly supply the necessary lubrication without interfering with his playing. While I have illustrated a selected embodiment of the invention, yet I do not wish to be limited to the constructional features shown.

I claim.

1. A trombone having inner tube portions communicating with the bell and mouthpiece respectively, a shoe portion having tubular legs telescoping over the inner tubes, an oil reservoir associated with each inner tube, and means actuated by the shoe for delivering oil from the reservoir onto the corresponding inner tube.

2. A trombone having inner tubes communi-

cating with the bell and mouthpiece respectively, a shoe portion telescoping over the inner tubes, an oil reservoir associated with each inner tube, each reservoir having a port, a valve normally closing each port, and means to open said valves by movement of the shoe.

3. A trombone having the inner tubes communicating with the bell and mouthpiece respectively, a shoe portion telescoping over said inner tubes, an oil reservoir associated with each inner tube, said reservoir being connected by a tubular brace member having a filling opening, a closure plug for said filling opening, each reservoir having a port, a valve closing each port, and means for opening said valve by movement of the shoe. 15

JOSEPH F. BURKE.
